UNITED STATES PATENT OFFICE.

FRÉDERICK W. SCHROEDER, OF LONDON, ENGLAND.

APPARATUS FOR SHAPING THE ENDS OF BILLIARD-CUES.

No. 840,716.

Specification of Letters Patent.

Patented Jan. 8, 1907.

Application filed November 2, 1905. Serial No. 285,529.

To all whom it may concern:

Be it known that I, FRÉDERICK W. SCHROEDER, of London, England, have invented a new and useful Apparatus for Shaping the 5 Ends of Billiard-Cues, of which the following is a full, clear, and exact description, reference being had to the accompanying drawings, forming part of this specification, in which—

- 10 Figure 1 is a longitudinal section of my improved device, showing the tip and bit in position therein. Fig. 2 is a side elevation of the device, partly broken away. Fig. 3 is a cross-section on the line III III of Fig. 1.
15 My invention relates to the shaping of the ends of billiard-cues to receive the tips; and the object of the invention is to provide a simple and cheap apparatus for centering and clamping the tip and for correctly guiding the bit which squares the end and shapes the receiving-hole.

In the drawings, 2 represents a steel tube having within it three flat springs 3, which are carried on pins 3' at each end, these pins being peened over at one side to prevent their drawing completely within the tube. These springs are preferably flaring or beveled slightly at the entering in to allow the tip to pass into the space between them.
25 Around that portion of the base-tube 2 containing the longitudinal springs are two sleeves 4 and 5. These sleeves are flared or provided with bell-mouths 6 and 7 at their opposite ends, and upon one of them is 30 screwed a sleeve 8, the opposite end of which abuts against the other sleeve. By screwing upon this sleeve 8 the flared sleeves may be simultaneously forced in opposite directions, thus compressing inwardly upon the beveled faces of the spring-pins. Beyond the 35 sleeves and springs the base-tube is preferably provided with a window 9, through which the end of the cue can be seen.

In using the apparatus, the sleeves being 45 loose upon the base-tube, the tip is forced into position where its end can be seen through the window. The sleeve 8 is then turned to force the flaring sleeves 4 and 5 apart, thus forcing the pins and springs inwardly and clamping the cue in position.

The bit 10 (shown in Fig. 1) is preferably provided with a stepped front portion 11 to form a stepped hole in the cue, the lip portions 12 squaring the front end of the cue.
50 A portion 13 of this bit is cylindrical and is a neat fit within the base-tube, which guides

and directs it. The bit may be used with an ordinary hand-stock.

The advantages of my invention result from the simplicity and efficiency of the apparatus. The cue may be quickly and easily centered and clamped in the guide device which centers the bit.

Many variations may be made in the form and arrangement of the radial clamping devices, the tubes, &c., without departing from my invention.

I claim—

1. In a cue-finishing device, a tubular support having longitudinal inner flat springs 70 with projecting pins at each end, a pair of sleeves arranged to act upon the pins, and means for simultaneously forcing the sleeves apart; substantially as described.

2. In apparatus of the character described, 75 two sets of radially-movable clamping devices, two oppositely-movable sleeves actuating said devices, and a screw device between the sleeves arranged to force them simultaneously in opposite directions with substantially equal pressure; substantially as described.

3. An apparatus for finishing billiard-cues comprising in one structure a tubular tool-guide adapted to receive interchangeable 85 tools, and a tubular support in alignment with said guide having internal longitudinal clamping-bars, a pair of external sleeves cooperating with said bars, and means operating to displace the said sleeves longitudinally relative to each other; substantially as described.

4. In apparatus of the character herein described a combined tool-guide and self-centering cue-grip comprising a cylindrical tube adapted to receive the tool at one end 95 and the end of the cue at the other, a plurality of clamping-bars within the cue end of the said tube, holes in the cue end of the tube and pins in the said clamping-bars projecting through the said holes, said pins having beveled heads, a pair of sleeves surrounding the tube and having flared ends adapted to cooperate with the beveled heads of the clamping-bar pins, and means for moving the said sleeves relatively to each other in an axial direction, substantially as described.

In testimony whereof I have hereunto set my hand.

F. W. SCHROEDER.
